DESIGN FOR A SPRING CLIP

Solomon Rosenberg, Los Angeles, Calif.

Application June 23, 1943, Serial No. 110,505

Term of patent 14 years

To all whom it may concern:

Be it known that I, Solomon Rosenberg, a citizen of the United States of America, residing in Los Angeles, county of Los Angeles, and State of California, have invented a new, original, and ornamental Design for Spring Clips, of which the following is a specification, reference being had to the accompanying drawing, forming a part thereof.

Fig. 1 is a side elevational view of a spring clip showing my new design.

Fig. 2 is an end view of the spring clip and Fig. 3 is a horizontal section taken on the line 3—3 of Fig. 1.

I claim:

The ornamental design for a spring clip, as shown.

SOLOMON ROSENBERG.
